Primary Examiner — Mark A Goodwin(74) *Attorney, Agent, or Firm* — Marshall, Gerstein & Borun LLP(57) **CLAIM**

The ornamental design for an excavator undercarriage, as shown and described.

DESCRIPTION

FIG. 1 is a top, front, and right-side isometric view of an excavator undercarriage showing the new design.

FIG. 2 is a top plan view of the excavator undercarriage.

FIG. 3 is a right-side elevation view of the excavator undercarriage.

FIG. 4 is a left-side elevation view of the excavator undercarriage.

FIG. 5 is a front elevation view of the excavator undercarriage; and,

FIG. 6 is a rear elevation view of the excavator undercarriage.

The broken lines depict portions of the excavator undercarriage that form no part of the claimed design.

1 Claim, 6 Drawing Sheets(56)
